PARACHUTE AND LIKE FLARE

Filed June 2, 1944

FIG.3.

UNITED STATES PATENT OFFICE

2,416,957

PARACHUTE AND LIKE FLARE

Conrad David Schermuly, Alfred James Schermuly, and Charles Schermuly, Parkgate, Newdigate, England, assignors to The Schermuly Pistol Rocket Apparatus Limited, Parkgate, Newdigate, England, a British company

Application June 2, 1944, Serial No. 538,505
In Great Britain December 17, 1942

6 Claims. (Cl. 102—35)

1

In the specification of our Patent No. 2,409,905 we have described a parachute-supported flare candle having hinged to the top thereof a number of ribs, each of which has hinged thereto a rib which extends beyond the top of the candle and is secured to a plate slidable on an extension secured to the candle case, the said ribs being covered with opaque material, so that when the flare is released, the "snatch" caused by the parachute opening moves the said ribs to a position inclined to the flare case and the covering thereon provides an effective screen.

Hitherto difficulty has been experienced in providing a screen which will remain open in the desired position because, owing to wind pressure, there has been a tendency for the screen to turn inside out. It is therefore the principal object of the present invention to provide an effective screen which will prevent upward glare from the flare and which will remain open in the desired position.

According to the present invention, the flare candle, together with the screen and its operating mechanism, is enclosed in a casing so arranged that the said casing falls apart at a predetermined time and allows the screen to operate.

A convenient form of the invention, given by way of example, will now be described with reference to the accompanying drawing in which Figure 1 shows the casing in section with the flare packed therein, some ribs of the screen and the opaque material attached thereto being omitted; Figure 2 shows the flare after the casing has been removed; and Fig. 3 is a fragmentary sectional view similar to Fig. 1 and showing a modified construction.

Referring to the drawing the casing 1 is of cylindrical shape and is divided axially and hinged at 2 at the bottom. Within the casing 1 there is packed a flare candle 3 having secured to the top an extension 4 provided with an axial slot 5. A pin 6 is provided in the slot 5 and on the pin 6 is supported a plate 7 which is preferably of greater diameter than the flare candle 3. The pin 6 is arranged to slide up and down in the slot 5 and at the same time allow the plate 7 to slide up and down with it.

Hinged to the top of the flare candle 3 are a number of ribs 8 covered with opaque material 9 to form a screen and hinged intermediate the ends of each of the ribs 8 is a rib 10 also covered with opaque material which extends beyond the top of the flare candle 3 and is hinged to the periphery of the plate 7. The latter covering is

2

arranged to form louvres over the main screen. The parachute cords 11 which lead to the parachute (not shown) supporting the flare are secured in any convenient manner to the pin 6 which slides in the slot 5.

When the complete device is packed in the divided casing 1 the plate 7 is pressed onto the top of the flare candle 3 and a lid 12 is placed over the open ends of the two halves of the casing 1 thereby holding them together as shown in Figure 1. As soon as the parachute opens a "snatch" will occur between the plate 7 and the parachute with the result that the plate 7 will be forced upwardly by the pin 6 sliding in the slot 5. In moving upwardly the plate 7 will remove the lid 12 from the casing 1 and allow it to open as shown in broken lines in Figure 1. As soon as this occurs the casing 1 will fall away from the device and allow the ribs 8 and 10 to open into the position shown in Figure 2.

If desired the lid 12 may be attached directly to the parachute cords 11 by cords 11a so that when the "snatch" occurs the cords 11 and 11a will pull the lid 12 from the casing 1.

By constructing the device in the said manner it will be seen that the flare and its screen become supported by the parachute before the screen is opened with the result that the strain is all taken by the parachute and none by the screen thereby preventing the screen from turning inside out.

We claim:

1. In combination, a flare candle, a screen secured to and surrounding said flare candle, a separable container enclosing said flare candle and screen, a lid over the upper end of said container to maintain the same closed, a parachute connected to said candle and means connected to said parachute for raising said lid when said parachute opens to allow said separable container to fall away and for opening said screen when said lid is raised.

2. A combination as claimed in claim 1 wherein said separable container is divided from top to bottom into two halves which are hinged together at the bottom.

3. In combination, a flare candle, a screen secured to and surrounding said flare candle, a slotted extension secured to the top of said flare candle, a pin adapted to slide vertically in said slot, a parachute secured to said pin, a separable container enclosing said flare candle and screen and arranged to open and fall away when unrestrained, a plate arranged over said pin to be raised vertically by said pin, means connecting

said plate with said screen so that the screen is opened as said plate is raised by said pin, a lid holding said separable container closed and arranged over said plate to be raised thereby from said container to allow said container to open and fall away, whereby when said parachute opens, the "snatch" of the same raises said pin whereby said lid is removed, the separable container falls away and the screen is opened.

4. A combination as claimed in claim 3 wherein the means connecting said plate with said screen comprises a plurality of ribs each secured at its upper end to said plate and at its lower end to said screen at a point intermediate the top and bottom of the same.

5. A combination as claimed in claim 3 wherein the means connecting said plate with said screen comprises a plurality of ribs each secured at its upper end to said plate and at its lower end to said screen at a point intermediate the top and bottom of the screen and a second screen surrounding said ribs and secured thereto. 20

6. A combination as claimed in claim 3 wherein said separable container is divided from top to bottom into two parts which are hinged at the bottom.
